DISPLAY PANEL AND DISPLAY DEVICE

CROSS-REFERENCE TO RELATED APPLICATION

This application is a continuation of U.S. application Ser. No. 18/090,103, filed on Dec. 28, 2022, which claims the priority of Chinese Patent Application No. 202211021496.1, filed on Aug. 24, 2022, the contents of both of which are incorporated by reference in their entirities.

TECHNICAL FIELD

The present disclosure generally relates to the field of display technologies and, more particularly, relates to a display panel and a display device.

BACKGROUND

With the development of the display technologies, while the display size of the display device is designed to be increased, different display areas can be designed to present different display contents at the same time, such as in a foldable mobile phone. When different display areas display different contents, the optimal refresh frequencies corresponding to different display areas are different. However, in the current display device, the screen refresh frequency of the entire display area is consistent, thus the display device cannot achieve an optimal display effect.

The present disclosed display panels and display devices are direct to solve one or more problems set forth above and other problems in the arts.

SUMMARY

One aspect of the present disclosure provides a display panel. The display panel includes a pixel circuit including a driving transistor and a preset module, a light-emitting element, a driving circuit, and a gating module. A first terminal of the preset module is connected to the driving transistor, a second terminal of the preset module is connected to a preset signal terminal or the driving transistor, a control terminal of the preset module is connected to a control signal line, and the control signal line is configured to receive a control signal. The driving circuit is configured to provide the control signal for the control signal line. The gating module is connected between the control terminal of the preset module and the driving circuit. The gating module is connected to a gating signal line, and the gating signal line is configured to receive a gating signal.

Another aspect of the present disclosure provides a display device. The display device includes a display panel. The display panel includes a pixel circuit including a driving transistor and a preset module, a light-emitting element, a driving circuit, and a gating module. A first terminal of the preset module is connected to the driving transistor, a second terminal of the preset module is connected to a preset signal terminal or the driving transistor, a control terminal of the preset module is connected to a control signal line, and the control signal line is configured to receive a control signal. The driving circuit is configured to provide the control signal for the control signal line. The gating module is connected between the control terminal of the preset module and the driving circuit. The gating module is connected to a gating signal line, and the gating signal line is configured to receive a gating signal.

Other aspects of the present disclosure can be understood by those skilled in the art in light of the description, the claims, and the drawings of the present disclosure.

5 BRIEF DESCRIPTION OF THE DRAWINGS

To illustrate the technical solutions in the embodiments of the present disclosure more clearly, the following briefly introduces the accompanying drawings used in the description of the embodiments. Obviously, the accompanying drawings in the following description are only some embodiments of the present disclosure, for those of ordinary skill in the art, other drawings can also be obtained from these drawings without creative effort.

10 FIG. 1 illustrates an exemplary display panel according to various disclosed embodiments of the present disclosure;

15 FIG. 2 illustrates another exemplary display panel according to various disclosed embodiments of the present disclosure;

20 FIG. 3 illustrates another exemplary display panel according to various disclosed embodiments of the present disclosure;

25 FIG. 4 illustrates another exemplary display panel according to various disclosed embodiments of the present disclosure;

30 FIG. 5 illustrates an exemplary pixel circuit structure according to various disclosed embodiments of the present disclosure;

35 FIG. 6 illustrates another exemplary pixel circuit structure according to various disclosed embodiments of the present disclosure;

40 FIG. 7 illustrates another exemplary pixel circuit structure according to various disclosed embodiments of the present disclosure;

45 FIG. 8 illustrates another exemplary display panel according to various disclosed embodiments of the present disclosure;

FIG. 22 illustrates another exemplary display panel according to various disclosed embodiments of the present disclosure;

FIG. 23 illustrates another exemplary display panel according to various disclosed embodiments of the present disclosure;

FIG. 24 illustrates another exemplary display panel according to various disclosed embodiments of the present disclosure;

FIG. 25 illustrates another exemplary display panel according to various disclosed embodiments of the present disclosure;

FIG. 26 illustrates another exemplary display panel according to various disclosed embodiments of the present disclosure; and

FIG. 27 illustrates an exemplary display device according to various disclosed embodiments of the present disclosure.

DETAILED DESCRIPTION

The technical solutions in the embodiments of the present disclosure will be clearly and completely described below with reference to the accompanying drawings in the embodiments of the present disclosure. Obviously, the described embodiments are only a part of the embodiments of the present disclosure, but not all of the embodiments. Based on the embodiments of the present disclosure, all other embodiments obtained by those of ordinary skill in the art without creative efforts shall fall within the protection scope of the present disclosure.

As described in the background art, with the development of the display technologies, while the display size of the display device is designed to be increased, different display areas can be designed to simultaneously present different display contents, such as a foldable mobile phone. When different display areas display different contents, the optimal refresh frequencies corresponding to different display areas are different. However, in the current display device, the screen refresh frequency of the entire display area is consistent, thus the display device cannot achieve an optimal display effect.

The present disclosure provides a display panel and a display device, which may effectively solve the existing technical problems. By optimizing the operating frequency of the gating module, it may be possible to realize different screen refresh frequencies in different display areas of the display panel without changing the pulse change frequency of the control signal outputted by the driving circuit of the display device to ensure the display effect of the display device.

To achieve the above purposes, the technical solutions provided by the embodiments of the present disclosure are as following, and the technical solutions provided by the embodiments of the present disclosure are described in detail with reference to FIG. 1 to FIG. 27.

The present disclosure provides a display panel. FIGS. 1-4 are schematic structural diagrams of four exemplary display panels according to various disclosed embodiments

of the present disclosure. As shown in FIGS. 1-4, an exemplary display panel may include a pixel circuit 100 and a light-emitting element 200. The pixel circuit 100 may include a driving transistor T0 and a preset module 10x. The first terminal 1 of the preset module 10x may be connected to a terminal of the driving transistor T0. The second terminal 2 of the preset module 10x may be connected to the preset signal terminal Kx or may be connected to the other terminal of the driving transistor T0. The control terminal d of the preset module 10x may be connected to a control signal line Sx, and the control signal line Sx may be configured for receiving a control signal.

The display panel may also include a gating module 300. The control terminal of the gating module 300 may be connected to a gating signal line S300, and the gating signal line S300 may be configured for receiving a gating signal.

In one embodiment, as shown in FIG. 1, the gating module 300 may be connected between the control terminal d of the preset module 10x and the control signal line Sx. In another embodiment, as shown in FIG. 2, the gating module 300 may be connected between the first terminal 1 of the preset module 10x and the driving transistor T0. In another embodiment, as shown in FIG. 3, when the second terminal 2 of the preset module 10x is connected to the preset signal terminal Kx, the gating module 300 may be connected between the second terminal 2 of the preset module 10x and the preset signal terminal Kx. In another embodiment, as shown in FIG. 4, when the second terminal 2 of the preset module 10x is connected to the driving transistor T0, the gating module 300 may be connected between the second terminal 2 of the preset module 10x and the driving transistor T0.

The pixel circuit 100 may be configured to generate a driving current to control the light-emitting element 200 to light up, and the preset module 10x in the pixel circuit 100 may be configured to provide corresponding functional signals for the driving transistor T0 to cooperate with other circuits connected to the driving transistor T0 to achieve the purpose of driving the transistor to generate a driving current to light up the light-emitting element 200. For example, after the pixel circuit 100 controls the light-emitting element 200 to light up, the pixel circuit 100 may maintain the current driving current when the preset module 10x stops working, such that the light-emitting element 200 may maintain the current "on" status, and finally the pixel where the pixel circuit is located may maintain the current display screen.

It may be seen from the above analysis that, in the technical solution provided by the exemplary embodiments of the present disclosure, a gating module may be disposed between the preset module and the control signal line, or between the preset module and the driving transistor, or between the preset module and the preset signal terminal. By optimizing the operation frequency of the gating module, the purpose of changing the operation frequency of the pixel circuit may be achieved. For example, the technical solution provided by the embodiments of the present disclosure may realize the refresh of the different display areas of the display panel on the basis of not changing the pulse change frequency of the output control signal of the driving circuit of the display device by optimizing the frequency of the gating module during the operation.

The technical solutions provided by the embodiments of the present disclosure will be described in detail below with reference to the structure of specific pixel circuits.

FIG. 5 illustrates an exemplary pixel circuit according to various disclosed embodiments of the present disclosure. As shown in FIG. 5, the pixel circuit of the display panel may

include a driving transistor **T0**, a reset module **101**, a data writing module **102**, a compensation module **103**, and a first light-emitting control module **1041**, a second light-emitting control module **1042**, a holding module **105** and an auxiliary reset module **106**. The first terminal of the reset module **101** may be connected to the gate of the driving transistor **T0** (or the first terminal of the reset transistor **T1**) and the second terminal of the reset module **101** may be connected to the second terminal of the driving transistor **T0** as shown by the dotted line in FIG. 5), and the second terminal of the reset module **101** may be connected to the reset signal terminal **Vref1**, and the control terminal of the reset module **101** may be connected to the reset control signal line **S1**. The reset module **101** may be configured to provide a reset signal for the driving transistor **T0**.

The first terminal of the data writing module **102** may be connected to the first terminal of the driving transistor **T0**, the second terminal of the data writing module **102** may be connected to the data signal terminal **Vdata**, and the control terminal of the data writing module **102** may be connected to the data writing control signal line **S2**. The data writing module **102** may be configured to provide a data signal for the driving transistor **T0**.

The first terminal of the compensation module **103** may be connected to the gate of the driving transistor **T0**, the second terminal of the compensation module **103** may be connected to the second terminal of the driving transistor **T0**, the control terminal of the compensation module **103** may be connected to the compensation control signal line **S3**. The compensation module **103** may be configured to compensate the threshold voltage deviation of the driving transistor **T0**.

The first terminal of the first light-emitting control module **1401** may be connected to the power supply voltage terminal **PVDD**, the second terminal of the first light-emitting control module **1401** may be connected to the first terminal of the driving transistor **T0**, and the control terminal of the first light-emitting control module **1401** may be connected to the light-emitting control signal line **S41**, the first terminal of the second light-emitting control module **1042** is connected to the second terminal of the driving transistor **T0**, the second terminal of the second light-emitting control module **1402** may be connected to the light-emitting element **200**, the control terminal of the second light-emitting control module **1402** may be connected to the second light-emitting control signal line **S42**. The enabling stages of the first light-emitting control signal line **S41** and the second light-emitting control signal line **S42** may be the same.

The first terminal of the holding module **105** may be connected to the power supply voltage terminal **PVDD**, and the second terminal of the holding module **105** may be connected to the gate of the driving transistor **T0**. The first terminal of the auxiliary reset module **106** may be connected to the auxiliary reset signal terminal **Vref2**, the second terminal of the auxiliary reset module **106** may be connected to the light-emitting element **200**, and the control terminal of the auxiliary reset module **106** may be connected to the auxiliary reset control signal line **S6**.

As shown in FIG. 6, the reset module **101** provided by an exemplary embodiment of the present disclosure may include a reset transistor **T1**. The first terminal of the reset transistor **T1** may be connected to the gate of the driving transistor **T0** (or the first terminal of the reset transistor **T1**) and the second terminal of the reset transistor **T1** may be connected to the second terminal of the driving transistor **T0** as shown by the dotted line in FIG. 6). The second terminal of the reset transistor **T1** may be connected to the reset signal terminal **Vref1**, and the control terminal of the reset transistor **T1** may be connected to the reset control signal line **S1**.

The data writing module **102** may include a data writing transistor **T2**. The first terminal of the data writing transistor **T2** may be connected to the first terminal of the driving transistor **T0**, the second terminal of the data writing transistor **T2** may be connected to the data signal terminal **Vdata**, and the control terminal of the data writing transistor **T2** may be connected to the data writing control signal line **S2**.

The compensation module **103** may include a compensation transistor **T3**. The first terminal of the compensation transistor **T3** may be connected to the gate of the driving transistor **T0**, the second terminal of the compensation transistor **T3** may be connected to the second terminal of the driving transistor **T0**, and the control terminal of the compensation transistor **T3** may be connected to the compensation control signal line **S3**.

The first light-emitting control module **1401** may include a first light-emitting control transistor **T41**.

The first terminal of the first light-emitting control transistor **T41** may be connected to the power supply voltage terminal **PVDD**, and the second terminal of the first light-emitting control transistor **T41** may be connected to the first terminal of the driving transistor **T0**, the control terminal of the first light-emitting control transistor **T41** may be connected to the first light-emitting control signal line **S41**. The second light-emitting control module **1042** may include a second light-emitting control transistor **T42**. The first terminal of the second light-emitting control transistor **T42** may be connected to the second terminal of the driving transistor **T0**. The second terminal of the second light-emitting control transistor **T42** may be connected to the light-emitting element **200**, the control terminal of the second light-emitting control transistor **T42** may be connected to the second light-emitting control signal line **S42**. The enabling stages of the first light-emitting control signal line **S41** and the second light-emitting control signal line **S42** may be the same. In one embodiment, the conduction types of the first light-emitting control transistor **T41** and the second light-emitting control transistor **T42** may be same, and both may be P-type or N-type. The first light-emitting control signal line **S41** and the second light-emitting control signal line **S42** may be the same signal line.

The holding module **105** may include a holding capacitor **C**. The first terminal of the holding capacitor **C** may be connected to the power supply voltage terminal **PVDD**, and the second terminal of the holding capacitor **C** may be connected to the gate of the driving transistor **T0**. The auxiliary reset module **106** may include an auxiliary reset transistor **T6**. The first terminal of the auxiliary reset transistor **T6** may be connected to the auxiliary reset signal terminal **Vref2**, the second terminal of the auxiliary reset transistor **T6** may be connected to the light-emitting element **200**, and the control terminal of the auxiliary reset transistor **T6** may be connected to the auxiliary reset control signal line **S6**.

Further, to optimize the performance of the pixel circuit, a bias adjustment module may also be included in the pixel circuit. FIG. 7 is a schematic structural diagram of another exemplary pixel circuit provided by an embodiment of the present disclosure. As shown in FIG. 7, the pixel circuit may further include a bias adjustment module **107**. The first terminal of the bias adjustment module **107** may be connected to the first terminal of the driving transistor **T0** (or the first terminal of the bias adjustment module **107** may be connected to the second terminal of the driving transistor **T0** as shown as dotted line in FIG. 7). The second terminal of the bias adjustment module **107** may be connected to the bias adjustment signal terminal **Vdh**, and the control terminal of the bias adjustment module **107** may be connected to the control signal terminal **S5**.

nal of the bias adjustment module 107 may be connected to the bias adjustment control signal line S7.

Further, as shown in FIG. 7, the bias adjustment module 107 provided by the embodiment of the present disclosure may include a bias adjustment transistor T7. The first terminal of the bias adjustment transistor T7 may be connected to the first terminal of the driving transistor T0 (or the first terminal of the bias adjustment transistor T7 may be connected to the second terminal of the driving transistor T0 as shown in the dotted line shown in FIG. 7). The second terminal of the bias adjustment transistor T7 may be connected to the bias adjustment signal terminal Vdh, and the control terminal of the bias adjustment transistor T7 may be connected to the bias adjustment control signal line S7.

It should be noted that the pixel circuits described above in the embodiments of the present disclosure are only a few of the circuits to which the present disclosure is applicable, and the present disclosure does not specifically limit this. In addition, the transistors in the pixel circuit shown in the above figures of the present disclosure are all illustrated by taking P-type transistors as an example; in other embodiments of the present disclosure, the transistors in the pixel circuit may also be N-type transistors; or, all the transistors in the pixel circuit may also be partly P-type transistors and partly N-type transistors, which are not specifically limited in the present disclosure.

FIG. 8 is a schematic structural diagram of another exemplary display panel provided by one embodiment of the present disclosure. As shown in FIG. 8, the preset module of the display panel provided by the embodiment of the present disclosure may be the data writing module 102. The first terminal of the data writing module 102 may be connected to the first terminal of the driving transistor T0. The preset signal terminal may include a data signal terminal Vdata. The second terminal of the data writing module 102 may be connected to the data signal terminal Vdata. The control signal line may include a data writing control signal line S2. The control terminal of the data writing module 102 may be connected to the data writing control signal line S2. The data writing module 102 may be configured to provide the data signal for the driving transistor T0. The gating module 300 provided in the embodiment of the present disclosure may be connected between the control terminal of the data writing module 102 and the data writing control signal line S2.

Further, as shown in FIG. 8, the gating module 300 provided by the embodiment of the present disclosure may access the control of the gating signal according to the gating signal line S300, and write data into the control signal line S2 and may be connected to the data writing transistor T2 when the gating signal is in the enabling stage. The data writing control signal line S2 may be disconnected from the data writing transistor T2 when the gate signal is in the non-enable stage. Therefore, when the current frame picture of the display panel is displayed, enabling the gate signal may allow the pixel circuit to complete the process of lighting the light-emitting element 200. In the subsequent preset frame number pictures, disabling the gate signal may cause the data signal not to be transmitted to the driving transistor T0, and finally the light-emitting element 200 may keep the lighting degree unchanged when the gating signal is enabled, such that the display screen is the same from the current frame to the preset number of frames, thereby realizing the purpose of the adjustment of the screen refresh rate of the display panel.

In other embodiments of the present disclosure, when the preset module is the data writing module, the gating module

may also be connected between the first terminal of the data writing module and the first terminal of the driving transistor, or the gating module may be connected between the second terminal of the data writing module and the data signal terminal, which needs to be specifically designed according to the actual application.

FIG. 9 illustrates a schematic structural diagram of another exemplary display panel according to various disclosed embodiments of the present disclosure. As shown in FIG. 9, the preset module of the display panel provided by the embodiment of the present disclosure may be a reset module 101. The first terminal of the reset module 101 may be connected to the gate of the driving transistor T0 (or the first terminal of the reset module 101 may be connected to the second terminal of the driving transistor T0 as shown as the dotted line shown in FIG. 9). The preset signal terminal may include a reset signal terminal Vref1. The second terminal of the reset module 101 may be connected to the reset signal terminal Vref1. The control signal line may include a reset control signal line S1. The control terminal of the reset module 101 may be connected to the reset control signal line S1. The reset module 101 may be configured for providing a reset signal for the driving transistor T0. The gating module 300 provided in the embodiment of the present disclosure may be connected between the control terminal of the reset module 101 and the reset control signal line S1.

Further, as shown in FIG. 9, the gating module 300 provided by the embodiment of the present disclosure can access the control of the gating signal according to the gating signal line S300, and may connect the reset control signal line S1 with the reset transistor T1 when the gating signal is in the enabling stage, and may disconnect the reset control signal line S1 from the reset transistor T1 when the gating signal is in the non-enable stage. Therefore, when the current frame picture of the display panel is displayed, the gating signal may be enabled to allow the pixel circuit to normally complete the process of lighting the light-emitting element 200. In the subsequent preset frame number pictures, the gating signal may be disabled such that the reset signal may not be transmitted to the driving transistor T0, and finally the light-emitting element 200 may be kept the lighting degree unchanged when the gating signal is enabled. Accordingly, the displayed screen of the display panel from the current frame to the preset number of frames may be same, thereby realizing the purpose of adjusting the screen refresh rate of the display panel.

In other embodiments of the present disclosure, when the preset module is the reset module, the gating module may also be connected between the first terminal of the reset module and the gate of the driving transistor, or the gating module may also be connected between the first terminal of the reset module and the second terminal of the driving transistor, or the gating module may be connected between the second terminal of the reset module and the reset signal terminal. The connection manner of the gating module may be specifically designed according to the actual application.

FIG. 10 illustrates a schematic structural diagram of another exemplary display panel provided by an embodiment of the present disclosure. As shown in FIG. 10, the preset module provided by the embodiment of the present disclosure may be a compensation module 103. The first terminal of the compensation module 103 may be connected to the gate of the driving transistor T0. The second terminal of the compensation module 103 may be connected to the second terminal of the driving transistor T0. The control signal line may include a compensation control signal line

S3. The gate of the compensation module 103 may be connected to the compensation control signal line S3. The compensation module 103 may be configured to compensate the threshold voltage deviation of the driving transistor T0. The gating module 300 provided in the embodiment of the present disclosure may be connected between the control terminal of the compensation module 103 and the compensation control signal line S3.

As shown in FIG. 10, the gating module 300 provided by the embodiment of the present disclosure may access the control of the gating signal according to the gating signal line S300, and connect the compensation control signal line S3 with the compensation transistor T3 when the gating signal is in the enabling stage, and disconnected the compensation control signal line S3 from the compensation transistor T3 when the gating signal is in the non-enable stage. Therefore, when the current frame picture of the display panel is displayed, the gating signal may be enabled such that the pixel circuit may normally complete the process of lighting the light-emitting element 200; and in the subsequent preset frame number pictures, the gating signal may be disabled such that the gate of the driving transistor T0 and its second terminal may not be communicated. Accordingly, the light-emitting element 200 may keep the lighting degree unchanged when the gating signal is enabled such that the display panel may have the same picture from the current frame to the preset number of frames. Thus, the purpose of adjusting the screen refresh frequency of the display panel may be achieved.

In other embodiments of the present disclosure, when the preset module is the compensation module, the gating module may also be connected between the first terminal of the compensation module and the gate of the driving transistor, or the gating module may also be connected to the compensation module between the second terminal of the compensation module and the second terminal of the driving transistor. The connection manner of the gating module may be specifically designed according to the actual application.

FIG. 11 is a schematic structural diagram of another exemplary display panel provided by an embodiment of the present disclosure. As shown in FIG. 11, the preset module provided by the embodiment of the present disclosure may be a bias adjustment module 107. The first terminal of the bias adjustment module 107 may be connected to the first terminal of the driving transistor T0 (or as shown as the dotted line in FIG. 11, the first terminal of the bias adjustment module 107 may be connected to the second terminal of the driving transistor T0). The preset signal terminal may include a bias adjustment signal terminal Vdh. The second terminal of the bias adjustment module 107 may be connected to the bias adjustment signal terminal Vdh. The control signal line may include a bias adjustment control signal line S7, and the control terminal of the bias adjustment module 107 may be connected to the bias adjustment control signal line S7. The bias adjustment module 107 may be configured to provide a bias adjustment signal for the driving transistor T0. The gating module 300 provided in the embodiment of the present disclosure may be connected between the control terminal of the bias adjustment module 107 and the bias adjustment control signal line S7.

Referring to FIG. 11, the gating module 300 provided by the embodiment of the present disclosure may access the control of the gating signal according to the gating signal line S300. When the gating signal is in the enabling stage, the bias adjustment control signal line S7 may be connected to the bias control signal line S7. When the gating signal is in the non-enable stage, the bias adjustment control signal

line S7 and the bias adjustment transistor T7 may be disconnected. Therefore, when the current frame picture of the display panel is displayed, the gating signal may be enabled such that the pixel circuit may normally complete the process of lighting the light-emitting element 200. In the subsequent preset frame number of pictures, the gating signal may be disabled such that the bias adjustment signal may not be transmitted to the driving transistor T0, and finally the light-emitting element 200 may keep the lighting degree unchanged when the gating signal is enabled. Accordingly, the display panel may have a same picture from the current frame to the preset number of frames, and the purpose of adjusting the screen refresh rate of the display panel may be achieved.

In other embodiments of the present disclosure, when the preset module is the bias adjustment module, the gating module may also be connected between the first terminal of the bias adjustment module and the first terminal of the driving transistor, or the gating module may also be connected between the first terminal of the bias adjustment module and the second terminal of the driving transistor, or the gating module may also be connected between the second terminal of the bias adjustment module and the bias adjustment signal terminal. The specific design of the gating module may be carried out according to the actual application.

In one embodiment of the present disclosure, in at least a portion of the operation process of the display panel provided by the present disclosure, the pulse change frequency of the gating signal may be F, and the pulse change frequency of the control signal may be Fc, and F≠Fc. Therefore, on the basis of keeping the pulse change frequency of the control signal Fc unchanged, by changing the pulse change frequency F of the gating signal, the lighting state of the light-emitting element of the pixel circuit connected with the gating module may be changed to achieve the purpose of the screen refresh frequency of the display panel. For example, under the condition of the pulse change frequency F, the gating signal of the current frame of the display panel may be set in the enabling stage such that the pixel circuit may control the light-emitting element to light normally, and display the screen at the corresponding pixel point. Then, in the time period of the subsequent preset number of frames of the display panel, the gating signal may be set to be disabled such that the preset module may transmit the relevant signal to the driving transistor such that the display screen of the pixel point from the current frame to the preset frame number of frames may be same. Accordingly, the purpose of adjusting the screen refresh frequency of the display panel may be achieved. In one embodiment, F<Fc, the duration of the enable stage of the gating signal may be shorter than the duration of the disabled stage.

FIG. 12 is a schematic structural diagram of another exemplary display panel provided by an embodiment of the present disclosure. As shown in FIG. 12, the display panel provided by an embodiment of the present disclosure may include a first display area A11 and a second display area A12. The pixel circuit may include a first pixel circuit 110 and a second pixel circuit 120. The first pixel circuit 110 may be connected to the light-emitting element 200 in the first display area A11, and the second pixel circuit 120 may be connected to the second pixel circuit 120 in the second display area A12. The light-emitting elements 200 of the display area A12 may be connected with each other.

It should be noted that the first display area A11 and the second display area A12 provided in the embodiment of the present disclosure may be two areas arranged along a first

direction, or the first display area **11** and the second display area **A12** may be two regions arranged along a second direction. The first direction may be the arrangement direction of multiple pixel circuit rows, and the second direction may be the extension direction of the pixel circuits in a single pixel circuit row. The arrangement of the first direction and the second direction is not specifically limited in the present disclosure.

As shown in FIG. 12, both the first pixel circuit **110** and the second pixel circuit **120** provided in this embodiment of the present disclosure may be connected to a gating module **300**. In at least a portion of the operation process of the display panel, the pulse change frequency of the gating signal received by the gating module **300** connected to the first pixel circuit **110** may be F_1 , and the pulse change frequency of the gating signal received by the gating module **300** connected to the second pixel circuit **120** may be F_2 , and $F_1 \neq F_2$. Therefore, in at least a portion of the operation process of the display panel, it may be possible to realize the adjustment of the different screen refresh frequencies of the first display area **A11** and the second display area **A12**. For example, the display area of the display panel corresponding to the higher frequency of F_1 and F_2 may be configured to display high-frequency images (such as high-frequency dynamic images), and the display area corresponding to the lower frequency of F_1 and F_2 may be configured to display low-frequency images (such as low-frequency static images). Such a configuration may satisfy that the different display areas of the display panel may display with different frequencies. At the same time, the power consumption of the display panel may also be reduced.

In one embodiment, the data refresh frequency of the first pixel circuit provided in the embodiment of the present disclosure is greater than the data refresh frequency of the second pixel circuit; and $F_1 > F_2$. The data refresh frequency is the frequency at which the pixel circuit successfully writes the data signal into the driving transistor and makes the driving transistor generate the driving current to the light-emitting element according to the data signal, that is, the data refresh frequency and at least one of the display refresh frequency and the pulse change of the strobe signal may be positively correlated. A larger data refresh frequency may correspond to a larger pulse change frequency of the gating signal, otherwise, a smaller data refresh frequency may correspond to a smaller pulse change frequency of the gating signal.

FIG. 13 is a schematic structural diagram of another exemplary display panel provided by an embodiment of the present disclosure. As shown in FIG. 13, the display panel provided by an embodiment of the present disclosure may include a first display area **A11** and a second display area **A12**. The pixel circuit of the display panel may include a first pixel circuit **110** and a second pixel circuit **120**. The first pixel circuit **110** may be connected to the light-emitting element **200** in the first display area **A11**, and the second pixel circuit **120** may be connected to the light-emitting element **200** in the second display area **A12**. One of the first pixel circuit **110** and the second pixel circuit **120** may not include a gating module, and the other one may include the gating module **300**. For example, one of the first pixel circuit **110** and the second pixel circuit **120** may be connected to the gating module **300**, while the other may not be connected to the gating module **300**.

It can be understood that in the first display area **A11** and the second display area **A12**, the screen refresh frequency of the display area corresponding to the pixel circuit connected with the gating module **300** may be positively correlated

with the pulse change frequency of the gating signal. The screen refresh frequency of the display area corresponding to the pixel circuit that is not connected to the gating module may be positively correlated with the data refresh frequency of the pixel circuit. Therefore, by optimizing the design of the pulse change frequency of the gating signal, the screen refresh rates of the first display area **A11** and the second display area **A12** may be adjusted differently.

As shown in FIG. 13, the data refresh frequency of the first pixel circuit **110** provided by the embodiment of the present disclosure may be greater than the data refresh frequency of the second pixel circuit **120**. The first pixel circuit **110** may not include the gating module **300**, and the second pixel circuit **120** may include the gating module **300**.

In FIGS. 14-21, the related technology in which the gating module **300** is connected between the control terminal **d** of the preset module **10x** and the control signal line **Sx** will be described in detail.

FIG. 14 is a schematic structural diagram of another exemplary display panel provided by an embodiment of the present disclosure. As shown in FIG. 14, the gating module **300** of the display panel provided by the embodiment of the present disclosure may be connected between the control terminal **d** of the preset module **10x** and the control signal lines **Sx**. The display panel may further include a driving circuit **400**, and the driving circuit **400** may be configured to provide the control signal for the control signal line **Sx**. The control signal required for the operation of the pixel circuit **100** provided by the embodiment of the present disclosure may be generated by the driving circuit **400**. The display panel may include a plurality of cascaded driving circuits **400**, and the cascaded driving circuits **400** may be arranged along a first direction **Y**. The first direction **Y** may be the arrangement direction of the multi-row pixel circuits, and the second direction **X** may be the extension direction of the pixel circuits in a single row.

FIG. 15 is a schematic structural diagram of another exemplary display panel provided by an embodiment of the present disclosure. As shown in FIG. 15, the display panel provided by an embodiment of the present disclosure may include a display area **AA** and a frame area **NA**. At least one of the driving circuit **400**, the gating module **300** and the gate signal line **S300** may be located in the frame **NA** area. The gating module **300** may be located at a side of the driving circuit **400** facing the display area **AA**. The gating module **300** may include a number **N** of gating transistors **T300**, and $N \geq 1$. The gate signal line **S300** may be connected to the gate of the gating transistor **T300**.

It can be understood that the gating module **300** provided in this embodiment of the present disclosure may be implemented by the gating transistors **T300**. When the gating module **300** includes a gating transistor **T300**, the first terminal of the gating transistor **T300** may be connected to the control signal line **Sx**, the second terminal of the gating transistor **T300** may be connected to the control terminal **d** of the preset module **10x**, and the gate of the gating transistor **T300** may be connected to the gate signal line **S300**. In some embodiments, when the gating module **300** includes multiple gating transistors **T300**, the multiple gating transistors **T300** may be connected in series and/or in parallel to form a switch controlled by a gating signal to realize the function of the gating module **300**.

FIG. 16 is a schematic structural diagram of another exemplary display panel provided by an embodiment of the present disclosure. As shown in FIG. 16, the conduction types of the gating transistors **T300** of different gating modules **300** provided by the embodiment of the present

disclosure may be same. The gate transistors **T300** may all be N-type transistors, or may all be P-type transistors. The gates of all the gating transistors **T300** provided by the embodiments of the present disclosure may be connected to the same gate signal line **S300**. Such a configuration may reduce wiring terminals and expand the effective wiring space of the display panel.

FIG. 17 is a schematic structural diagram of another exemplary display panel provided by an embodiment of the present disclosure. As shown in FIG. 17, a number P rows of pixel circuits **100** of the display panel provided by the embodiment of the present disclosure may be connected to the same gating module **300**, and $P \geq 1$. The driving circuit **400** provided in this embodiment of the present disclosure may drive at least one row of pixel circuits **100**. When the driving circuit **400** drives a single row of pixel circuits **100**, the pixel circuits **100** in the row may all be connected to the same gating module **300**. When the driving circuit **400** drives multiple rows of pixel circuits **100** at the same time (taking two rows of pixel circuits **100** as an example in FIG. 17), the multiple rows of pixel circuits **100** may all be connected to the same gating module **300**. Accordingly, the number of gating modules **300** may be reduced; and ensuring that the wiring space of the display panel may be relatively large.

FIG. 18 is a schematic structural diagram of another exemplary display panel provided by an embodiment of the present disclosure. As shown in FIG. 18, the display panel provided by an embodiment of the present disclosure may include a display area **AA** and a frame area **NA**. The gating module **300** may be located in the display area **AA**. One of the pixel circuits **100** may include at least one gating module **300**. It can be understood that when the gating module **300** provided in the embodiment of the present disclosure is disposed in the display area, any one of the pixel circuits **100** whose data refresh frequency needs to be changed may be connected to at least one gating module **300**. In one embodiment, the conduction types of the gating transistors **T300** in different gating modules **300** may be same, and the gates of the gating transistors **T300** in different gate modules **300** may be connected to the same gating signal line **S300**.

FIG. 19 is a schematic structural diagram of another exemplary display panel provided by an embodiment of the present disclosure. The display panel provided by an embodiment of the present disclosure may include a display area **AA** and a frame area **NA**. The gating module **300** may be located in the display area **AA**. A number T of pixel circuits **100** may be connected to the same gating module **300**, and $T \geq 2$. By connecting multiple pixel circuits **100** to the same gating module **300**, not only a relatively large wiring space of the display panel may be ensured, but also the influence of too many gating modules **300** on the pixel aperture ratio of the display panel may be reduced.

FIG. 20 is a schematic structural diagram of another exemplary display panel provided by an embodiment of the present disclosure. As shown in FIG. 20, the preset module of the display panel provided by the embodiment of the present disclosure may include a first preset module **10x1** and a second preset module **10x2**. At least one terminal of the first preset module **10x1** and at least one terminal of the second preset module **10x2** may be connected to different nodes. The gating module may include a first gating module **310** and a second gating module **320**. The control signal line may include a first control signal line **Sx1** and a second control signal line **Sx2**. The control terminal **d** of the first preset module **10x1** may be connected to the first gating module **310**, and may be connected to the first control signal line **Sx1**. The control terminal **d** of the second preset module

10x2 may be connected to the second gating module **320**, and may be connected to the second control signal line **Sx2**.

In one embodiment of the present disclosure, the control terminal of the first gating module **310** provided by the present disclosure and the control terminal of the second gating module **320** may receive a same gating signal. When the conduction type of the gating transistor **T300** included in the first gating module **310** and the gating transistor **T300** included in the second gate module **320** are same, the control terminal of the first gating module **310** and the control terminal of the gating transistor of the second gating module **320** may be connected to the same gating signal line **S300**. Such a configuration may reduce wiring terminals and may ensure a relatively large wiring space.

The embodiments of the present disclosure do not specifically limit the types of the first preset module and the second preset module. As shown in FIG. 21, which is a schematic structural diagram of another exemplary display panel provided by an embodiment of the present disclosure, the display panel provided by the present disclosure may include a data writing module **102**, a reset module **101** and a compensation module **103**. The first terminal of the data writing module **102** may be connected to the first terminal of the driving transistor **T0**, the second terminal of the data writing module **102** may be connected to the data signal terminal **Vdata**, and the control terminal of the data writing module **102** may be connected to the data writing control signal line **S2**. The data writing module **102** may be configured to provide data signals for the driving transistor **T0**. The first terminal of the reset module **101** may be connected to the gate of the driving transistor **T0** (or the first terminal of the reset module **101** may be connected to the second terminal of the driving transistor **T0** as shown by the dotted line in FIG. 5), and the second terminal of the reset module **101** may be connected to the reset signal terminal **Vref1**, and the control terminal of the reset module **101** may be connected to the reset control signal line **S1**. The reset module **101** may be configured for providing a reset signal for the driving transistor **T0**. The first terminal of the compensation module **103** may be connected to the gate of the driving transistor **T0**, the second terminal of the compensation module **103** may be connected to the second terminal of the driving transistor **T0**, the control terminal of the compensation module **103** may be connected to the compensation control signal line **S3**. The compensation module **103** may be configured to compensate the threshold voltage deviation of the driving transistor **T0**.

As shown in FIG. 21, the first preset module provided by the embodiment of the present disclosure may be the data writing module **102**, and the second preset module may be the reset module **101**. In other embodiments of the present disclosure, the first preset module may be a data writing module, and the second preset module may be a compensation module; or, the first preset module may be a reset module, and the second preset module may be a compensation module.

FIGS. 22-25 describe the exemplary embodiments in which the gating module **300** may be connected between the first terminal of the preset module **10x** and the driving transistor **T0**, or the gating module **300** may be connected between the second terminal of the preset module **10x** and the preset module **10x** or the driving transistor **T0** in detail.

In one embodiment of the present disclosure, the gating module may be connected between the first terminal of the preset module and the driving transistor. FIG. 22 is a schematic structural diagram of another exemplary display panel provided by an embodiment of the present disclosure.

As shown in FIG. 22, the preset module of the display panel may include a third preset module **10x3** and a fourth preset module **10x4**. At least one terminal of the third preset module **10x3** and at least one terminal of the fourth preset module **10x4** may be connected to different nodes. The control terminal of the third preset module **10x3** may be connected to the third control signal line **Sx3**, and the control terminal of the fourth preset module **10x4** may be connected to the fourth control signal line **Sx4**. The gating module may include a third gating module **330** and a fourth gating module **340**. The third gating module **330** may be connected between the first terminal of the third preset module **10x3** and the driving transistor **T0**. The fourth gating module **340** may be connected between the first terminal of the fourth preset module **10x4** and the driving transistor **T0**.

In another embodiment, the gating module provided in the embodiment of the present disclosure is connected between the second terminal of the preset module and the preset signal terminal or the driving transistor. FIG. 23 is a schematic structural diagram of another display panel provided by an embodiment of the present disclosure. As shown in FIG. 23, the preset module of the display panel may include a third preset module **10x3** and a fourth preset module **10x4**. At least one terminal of the third preset module **10x3** and at least one terminal of the fourth preset module **10x4** may be connected to different nodes. The control terminal of the third preset module **10x3** may be connected to the third control signal line **Sx3**. The control terminal of the fourth preset module **10x4** may be connected to the fourth control signal line **Sx4**. The gating module may include a third gating module **330** and a fourth gating module **340**. The third gating module **330** may be connected between the second terminal of the third preset module **10x3** and the preset signal terminal **Kx** or the driving transistor **T0**. The fourth gating module **340** may be connected between the second terminal of the fourth preset module **10x4** and the preset signal terminal **Kx** or the driving transistor **T0**.

In one embodiment of the present disclosure, the control terminal of the third gating module **330** and the control terminal of the fourth gating module **340** may receive the same gating signal. When the conduction types of the gating transistor **T300** included in the third gating module **330** and the gating transistor **T300** included in the fourth gating module **340** are same, the control terminal of the third gating module **330** and the control terminal of the fourth gating module **340** may be connected to the same gating signal line **S300**. Accordingly, the wiring terminals may be reduced, and a relatively large wiring space may be ensured.

The present disclosure does not limit the types of the third preset module and the fourth preset module. As shown in FIG. 24, which is a schematic structural diagram of another exemplary display panel provided by an embodiment of the present disclosure, the display panel provided by the present disclosure may include a data writing module **102**, a reset module **101** and a compensation module **103**. The first terminal of the data writing module **102** may be connected to the first terminal of the driving transistor **T0**, the second terminal of the data writing module **102** may be connected to the data signal terminal **Vdata**, and the control terminal of the data writing module **102** may be connected to the data writing control signal line **S2**. The data writing module **102** may be used to provide data signals for the driving transistor **T0**. The first terminal of the reset module **101** may be connected to the gate of the driving transistor **T0** (or the first terminal of the reset module **101** may be connected to the second terminal of the driving transistor **T0** as shown by the dotted line in FIG. 5), and the second terminal of the reset

module **101** may be connected to the reset signal terminal **Vref1**, and the control terminal of the reset module **101** may be connected to the reset control signal line **S1**. The reset module **101** may be configured for providing a reset signal for the driving transistor **T0**. The first terminal of the compensation module **103** may be connected to the gate of the driving transistor **T0**, the second terminal of the compensation module **103** may be connected to the second terminal of the driving transistor **T0**, the control terminal of the compensation module **103** may be connected to the compensation control signal line **S3**. The compensation module **103** may be configured to compensate the threshold voltage deviation of the driving transistor **T0**.

As shown in FIG. 24, the third preset module may be a reset module **101**, and the fourth preset module may be a compensation module **103**. In other embodiments of the present disclosure, the third preset module provided by the present disclosure may be a data writing module, and the fourth preset module may be a reset module. In other embodiments, the third preset module may be a data writing module, and the fourth preset module may be a compensation module.

As shown in FIG. 25, which is a schematic structural diagram of another exemplary display panel provided by the embodiment of the present disclosure, the third preset module of the display panel provided by the embodiment of the present disclosure may be the reset module **10**, and the fourth preset module may be the compensation module **103**. One terminal of the reset module **101** and one terminal of the compensation module **103** may be connected to one terminal of the same gating module **300**, and the other terminal of the gating module **300** may be connected to the gate of the driving transistor **T0**. In such a configuration, the number of gating modules **300** may be reduced, and a large wiring space may be ensured.

FIG. 26 is a schematic structural diagram of another exemplary display panel provided by an embodiment of the present disclosure. As shown in FIG. 26, the preset module of the display panel provided by the embodiment of the present disclosure may be the compensation module **103**. The pixel circuit of the display panel may further include a composite adjustment module **108**. The first terminal of the composite adjustment module **108** may be connected to the second terminal of the driving transistor **T0**, the second terminal of the composite adjustment module **108** may be connected to the composite adjustment signal terminal **Vf**, and the control terminal of the composite adjustment module **108** may be connected to the composite adjustment signal terminal **S8**. The gating module **300** may be connected between the first terminal of the compensation module **103** and the gate of the driving transistor **T0**, or the gating module **300** may be connected between the second terminal of the compensation module **103** and the second terminal of the driving transistor **T0**.

As shown in FIG. 26, the composite adjustment module **108** may include a composite adjustment transistor **T8**. The first terminal of the composite adjustment transistor **T8** may be connected to the second terminal of the driving transistor **T0**, the second terminal of the composite adjustment transistor **T8** may be connected to the composite adjustment signal terminal **Vf**, and the gate of the composite adjustment transistor **T8** may be connected to the composite adjustment control signal terminal **S8**.

It can be understood that the composite adjustment module **108** provided in the embodiment of the present disclosure may multiplex the reset module and a set of bias adjustment modules. During the reset stage, the composite

adjustment signal terminal Vf may output a reset signal, and the composite adjustment module 108 may transmit the reset signal to the second terminal of the driving transistor T0, the reset signal may be transmitted to the gate of the driving transistor T0 through the compensation module 103 and the gating module 300 for reset. In the bias adjustment stage, the composite adjustment signal terminal Vf may output the bias adjustment signal, and the composite adjustment module 108 may transmit the bias adjustment signal to the second terminal of the driving transistor T0.

For example, the operation process of the pixel circuit provided by the embodiment of the present disclosure may include a reset stage and a bias adjustment stage. In the reset stage, the composite adjustment signal terminal Vf may provide a reset signal, and when the composite adjustment module 108, the compensation module 103 and the gating module 300 are all turned on, the gate of the driving transistor T0 may receive the reset signal. In the bias adjustment stage, the composite adjustment module 108 may be turned on, and the composite adjustment signal terminal Vf may provide a bias adjustment signal. The voltage value of the reset signal may be different from the voltage value of the bias adjustment signal.

In one embodiment of the present disclosure, in the bias adjustment stage, at least one of the compensation module 103 and the gating module 300 may be turned off, or both of them may be turned off, thus the path between the second terminal and the gate of the driving transistor T0 may be turned off to prevent the bias adjustment signal from affecting the gate potential of the driving transistor T0.

In one embodiment of the present disclosure, the control terminal of the composite adjustment module 108 may receive a composite adjustment control signal, and the pulse change frequency of the composite adjustment control signal may be greater than the pulse change frequency of the gating signal. Setting the pulse change frequency of the composite adjustment control signal to be greater than the pulse change frequency of the gating signal may be able to, on the basis that the gating signal may adjust the data refresh frequency of the pixel circuit, control the pixel circuit to operate normally through the composite adjustment control signal in the enabling stage of the gating signal.

The present disclosure also provides a display device. The display device may include one of the present disclosed display panels, or other appropriate display panel.

FIG. 27 is a schematic structural diagram of an exemplary display device provided by an embodiment of the present disclosure. The display device 1000 provided by an embodiment of the present disclosure may be a mobile terminal device.

In some embodiments, the display device provided by the present disclosure may also be an electronic display device, such as a computer and a wearable display device, which is not specifically limited by the present disclosure.

Embodiments of the present disclosure provide a display panel and a display device. In a pixel circuit of the display panel, a gating module may be disposed between a preset module and a control signal line, or between a preset module and a driving transistor, or between the preset module and the preset signal terminal. By optimizing the operation frequency of the gating module, the purpose of changing the operation frequency of the pixel circuit may be achieved. For example, the technical solution provided by the embodiment of the present disclosure may realize the refresh of operation frequencies of different display areas of the display panel on the basis of not changing the pulse change frequency of the output control signal of the driving circuit

of the display device by optimizing the frequency of the gating module during the operation. Accordingly, the driving display effect of the display device may be ensured as expected.

5 In the description of the present disclosure, it is to be understood that the terms "center", "longitudinal", "lateral", "length", "width", "thickness", "upper", "lower", "front" "back", "left", "right", "vertical", "horizontal", "top", "bottom", "inside", "outside", "clockwise", "counterclockwise",

10 "axial", "radial", and "circumferential", etc. indicate the orientation or positional relationship based on the orientation or positional relationship shown in the accompanying drawings, which are only for the convenience of describing the present disclosure and simplifying the description, rather than indicating or implying the indicated device or elements must have a particular orientation, be constructed and operate in a particular orientation, and therefore should not be construed as limiting the present disclosure.

15 20 Furter, the terms "first" and "second" are only for descriptive purposes only, and should not be understood as indicating or implying relative importance or implying the number of indicated technical features. Thus, a feature delimited with "first", or "second" may expressly or implicitly include at least one of those features. In the description of the present disclosure, "plurality" means at least two, such as two, three, etc., unless otherwise expressly and specifically defined.

25 30 In the present disclosure, unless otherwise expressly specified and limited, such terms as "installed", "connected", "bonded" and "fixed" should be understood in a broad sense, for example, it may be a fixed connection or a detachable connection. It can be a mechanical connection or a connection or communication with each other. It can be directly connected or indirectly connected through an intermediate medium, or it can be the internal communication of two elements or the interaction relationship between the two elements, unless otherwise expressly qualified. For those of 35 40 ordinary skill in the art, the specific meanings of the above terms in the present disclosure can be understood according to specific situations.

45 50 In the present disclosure, unless otherwise expressly specified and limited, a first feature "on" or "under" a second feature may be in direct contact between the first and second features, or the first and second features indirectly through an intermediary contact. Also, the first feature being "above", "over" and "on" the second feature may mean that the first feature is directly above or obliquely above the second feature, or simply means that the first feature is level higher than the second feature. The first feature being "below", "under" and "beneath" the second feature may mean that the first feature is directly below or obliquely below the second feature, or simply means that the first 55 feature has a lower level than the second feature.

55 60 In the present disclosure, when the terms "one embodiment", "some embodiments", "example", "specific example", or "some examples", etc. appear, they may mean the specific features, and structures included in at least one embodiment or example of the present disclosure. In this specification, schematic representations of the above terms are not necessarily directed to the same embodiment or example. Furthermore, the particular features, structures, materials or characteristics described may be combined in any suitable manner in any one or more embodiments or examples. Furthermore, those skilled in the art may combine and combine the different embodiments or examples

19

described in this specification, as well as the features of the different embodiments or examples, without conflicting each other.

Although the embodiments of the present disclosure have been shown and described above, it should be understood that the above-mentioned embodiments are exemplary and should not be construed as limiting the present disclosure. Embodiments are subject to variations, modifications, substitutions and variations by those skilled in the art.

What is claimed is:

1. A display panel comprising:
  - a pixel circuit including a driving transistor and a preset module, a first terminal of the preset module being connected to the driving transistor, a second terminal of the preset module being connected to a preset signal terminal or the driving transistor, a control terminal of the preset module being connected to a control signal line, and the control signal line being configured to receive a control signal;
  - a light-emitting element;
  - a driving circuit configured to provide the control signal for the control signal line; and a gating module connected between the control terminal of the preset module and the driving circuit, the gating module being connected to a gating signal line, and the gating signal line being configured to receive a gating signal, wherein the gating module is connected between the driving circuit and the control signal line, the control signal line is connected between the gating module and the control terminal of the preset module, and the gating module is located in a frame area of the display panel,
  - wherein the gating module includes a first gating module and a second gating module, the preset module in a same pixel circuit includes a first preset module and a second preset module, the first gating module is connected to the first preset module, and the second gating module is connected to the second preset module, and wherein the first gating module and the second gating module are connected to a same gating signal line.
2. The display panel according to claim 1, wherein:
  - the preset module is a data writing module, a first terminal of the data writing module is connected to a first terminal of the driving transistor, the preset signal terminal includes a data signal terminal, a second terminal of the data writing module is connected to the data signal terminal, and the data writing module is configured to provide a data signal for the driving transistor; or
  - the preset module is a reset module, a first terminal of the reset module is connected to a gate or a second terminal of the driving transistor, the preset signal terminal includes a reset signal terminal, a second terminal of the reset module is connected to the reset signal terminal, and the reset module is configured to provide a reset signal for the driving transistor; or
  - the preset module is a compensation module, a first terminal of the compensation module is connected to the gate of the driving transistor, and a second terminal of the compensation module is connected to the second terminal of the driving transistor; or
  - the preset module is a bias adjustment module, a first terminal of the bias adjustment module is connected to the first terminal or the second terminal of the driving transistor, the preset signal terminal includes a bias adjustment signal terminal, a second terminal of the bias adjustment module is connected to the bias adjust-

20

ment signal terminal, and the bias adjustment module is configured to provide a bias adjusting signal for the driving transistor.

3. The display panel according to claim 1, wherein:
  - in at least a portion of an operation process of the display panel, a pulse change frequency of the gating signal is F , and a pulse change frequency of the control signal is F_C , and FF_C .
4. The display panel according to claim 3, wherein:
  $F < F_C$.
5. The display panel according to claim 1, wherein:
  - the gating module includes one or more gating transistors.
6. The display panel according to claim 5, wherein:
  - the gating signal line is connected to a gate of at least one of the one or more gating transistors; and/or
  - at least one of the one or more gating transistors is a P-type transistor or at least one of the one or more gating transistors is an N-type transistor; and/or
  - the gating module includes a plurality of gating transistors, the plurality of gating transistors being connected in series and/or in parallel.
7. The display panel according to claim 1, wherein:
  - a plurality of pixel circuits are connected to a same gating module; and/or
  - one or more pixel circuits are connected to a same gating module.
8. The display panel according to claim 1, wherein:
  - the driving circuit is configured to provide the control signal to one or more pixel circuits, the one or more pixel circuits being connected to a same gating module.
9. The display panel according to claim 1, further comprising:
  - a display area;
  - wherein:
    - the gating module is located at a side of the driving circuit facing the display area; and/or
    - the gating signal line is located at a side of the driving circuit facing the display area.
10. The display panel according to claim 1, further comprising:
  - a display area; and
  - the frame area;
  - wherein at least one of the driving circuit, or the gating signal line is located in the frame area.
11. The display panel according to claim 1, wherein:
  - at least one terminal of the first preset module and at least one terminal of the second preset module are connected to different nodes.
12. The display panel according to claim 11, wherein:
  - the control signal line includes a first control signal line and a second control signal line; and
  - a control terminal of the first preset module is connected to the first gating module and connected to the first control signal line, and a control terminal of the second preset module is connected to the second gating module and connected to the second control signal line.
13. The display panel according to claim 12, wherein:
  - a control terminal of the first gating module and a control terminal of the second gating module are configured to receive a same gating signal.
14. The display panel according to claim 11, further comprising:
  - a data writing module;
  - a reset module; and
  - a compensation module;

wherein:

a first terminal of the data writing module is connected to a first terminal of the driving transistor, the preset signal terminal includes a data signal terminal, a second terminal of the data writing module is connected to the data signal terminal, and the data writing module is configured to provide a data signal for the driving transistor;

a first terminal of the reset module is connected to a gate or a second terminal of the driving transistor, the preset signal terminal includes a reset signal terminal, a second terminal of the reset module is connected to the reset signal terminal, and the reset module is configured to provide a reset signal for the driving transistor;

a first terminal of the compensation module is connected to the gate of the driving transistor, a second terminal of the compensation module is connected to a second terminal of the driving transistor; and

at least one of:

the first preset module is the data writing module, and the second preset module is the reset module; the first preset module is the data writing module, and the second preset module is the compensation module; or

the first preset module is the reset module, and the second preset module is the compensation module.

15. The display panel according to claim 1, further comprising:

a first display area; and
a second display area;

wherein:

the pixel circuit includes a first pixel circuit and a second pixel circuit, the first pixel circuit is connected to the light-emitting element in the first display area, and the second pixel circuit is connected to the light-emitting element in the second display area;

in at least a portion of an operation process of the display panel, a pulse change frequency of the gating signal received by the gating module connected to the first pixel circuit is F_1 , and a pulse change frequency of the gating signal received by the gating module connected to the second pixel circuit is F_2 ;

$F_1 \neq F_2$.

16. The display panel according to claim 15, wherein: a data refresh frequency of the first pixel circuit is greater than a data refresh frequency of the second pixel circuit; and

$F_1 > F_2$.

17. The display panel according to claim 1, further comprising:

a first display area; and
a second display area;

wherein:

the pixel circuit includes a first pixel circuit and a second pixel circuit, the first pixel circuit is connected to the light-emitting element in the first display area, and the second pixel circuit is connected to the light-emitting element in the second display area;

one of the first pixel circuit and the second pixel circuit is not connected to the gating module, and another

one of the first pixel circuit and the second pixel circuit is connected to the gating module.

18. A display device comprising: a display panel including:

a pixel circuit including a driving transistor and a preset module, a first terminal of the preset module being connected to the driving transistor, a second terminal of the preset module being connected to a preset signal terminal or the driving transistor, a control terminal of the preset module being connected to a control signal line, and the control signal line being configured to receive a control signal;

a light-emitting element;

a driving circuit configured to provide the control signal for the control signal line; and

a gating module connected between the control terminal of the preset module and the driving circuit, the gating module being connected to a gating signal line, and the gating signal line being configured to receive a gating signal,

wherein the gating module is connected between the driving circuit and the control signal line, the control signal line is connected between the gating module and the control terminal of the preset module, and the gating module is located in a frame area of the display panel,

wherein the gating module includes a first gating module and a second gating module, the preset module in a same pixel circuit includes a first preset module and a second preset module, the first gating module is connected to the first preset module, and the second gating module is connected to the second preset module, and wherein the first gating module and the second gating module are connected to a same gating signal line.

19. A display panel comprising:

a pixel circuit including a driving transistor and a preset module, a first terminal of the preset module being connected to the driving transistor, a second terminal of the preset module being connected to a preset signal terminal or the driving transistor, a control terminal of the preset module being connected to a control signal line, and the control signal line being configured to receive a control signal;

a light-emitting element;

a driving circuit configured to provide the control signal for the control signal line; and

a gating module connected between the control terminal of the preset module and the driving circuit, the gating module being connected to a gating signal line, and the gating signal line being configured to receive a gating signal,

wherein the driving circuit is configured to provide the control signal to a row of pixel circuits, the row of pixel circuits being connected to a same gating module,

wherein the gating module includes a first gating module and a second gating module, the preset module in a same pixel circuit includes a first preset module and a second preset module, the first gating module is connected to the first preset module, and the second gating module is connected to the second preset module, and wherein the first gating module and the second gating module are connected to a same gating signal line.

20. A display device comprising the display panel of claim 19.
